SEWING MACHINE DRIVE

Filed Jan. 23, 1924

INVENTOR

John Holtzman

UNITED STATES PATENT OFFICE

JOHN HOLTZMAN, OF NEW YORK, N. Y.

SEWING MACHINE DRIVE

Application filed January 23, 1924. Serial No. 688,042.

This invention relates to improvements in sewing machine drive devices, particularly electric motor installations as applied to individual domestic machines.

5 One of the objects of the invention is to provide a motor so mounted as to be adjustable on the sewing machine stand, relative to its hand wheel, the motor carrying frame being void of fastenings which might mu-
10 tilate or disfigure the stand.

Another purpose is to produce a driving device in which the motor is directly applied to the hand wheel through friction rolls in such manner as to transmit rotary
15 motion in a positive and practical manner.

A further aim is in the provision of a motor drive that can be readily applied to any ordinary type of domestic sewing machine in a simple manner, without tools or
20 mechanical appliances and which is eco-
nominally manufactured.

These and other like aims and objects are accomplished by the novel construction and combination of parts hereinafter de-
25 scribed and shown in the accompanying drawings, forming an essential part of this disclosure, and in which:

Figure 1 is a side view showing an adaptation of the device illustrated in Figure 2, in which a three point contact is made with the hand-wheel.

Figure 2 is an offset sectional view taken in planes represented by the line 2-2 of Figure 1.

35 Referring more in detail to the drawings, the numeral 20 designates throughout a level stand or table on which the sewing machine body is secured, the same having a horizontal shaft on the extending end of
40 which the hand-wheel 23 is fixed, these parts being conventional in type.

The drawings show a bracket 75 having a rubber base 76 but disposed centrally below the axis of the hand-wheel 23.

45 In the upper portion of this hollow bracket is carried a motor 77 having a vertical shaft 78 having on its extending end a wheel 79 provided with a rubber cover or ring 80 adapted to frictionally engage the hand wheel on its outer side.

A pair of angularly disposed rubber cov-
ered rolls 81 are freely rotatable on studs
82 arranged radially of the axis of the hand-
wheel, on the side opposite the driver or
ring 80, these studs having shoulders 83 be-
low which are arms 84 having inreaching
hubs 85.

Pivot screws 86 pass through the hubs to engage the sides of the motor casing, allowing the idle rolls 81 to swing towards or
from the hand-wheel as shown.

The lower ends of the arms 84 are con-
nected by a cross bar 87 having at its center
a forked lug 88 through which passes a bolt
89, pivoted at 90 to the bracket and pro-
vided with an adjusting nut 91 for moving
the rolls 81 relative to the driving wheel 79.

It is to be noted that advantage is taken
of the weight of the motor and associated
parts to keep the device from shifting and
that this effect is greatly enhanced by the
rubber edged base of the device, the same
acting to produce a suctional effect in addi-
tion to its non-slipping qualities.

The foregoing disclosure is to be regarded
as descriptive and illustrative only, and not
as restrictive or limitative of the invention,
of which obviously an embodiment may be
constructed including many modifications
without departing from the general scope
herein indicated and denoted in the appended
claims.

Having this described my invention, what
I claim as new and desire to secure by Let-
ters Patent, is:

1. A driving device for a machine having
a hand-wheel, comprising a bracket, a mo-
tor mounted in the bracket, a friction wheel
fixed on the shaft of said motor, said wheel
engaging one side of the hand-wheel, a
frame pivoted to said bracket, said frame
having a pair of forks disposed in radial
relation to the axis of the hand-wheel on the
side opposite said friction wheel, rolls rev-
oluble on said forks, and means for adjust-
ing said frame to cause said rolls to grip
said hand-wheel.

2. A driving device for a machine having
a hand-wheel, comprising a bracket, a motor
mounted in the bracket, a friction wheel
adapted to frictionally engage the hand
wheel on its outer side.

- driven by said motor, said friction wheel impinging the hand-wheel, idle rolls impinging the opposite side of the hand wheel at points uniformly remote from the friction wheel, said friction wheel and rolls constituting a three point contact with the hand wheel, and means for adjusting the pressure of said rolls as opposed to said friction wheel.
- 10 3. A wheel driving device comprising in combination with a machine wheel, a bracket and a motor, said motor being mounted on said bracket, of a shaft for said motor, a friction roll fixed on said shaft to contact the side of the machine wheel, a frame pivoted to the bracket, a roll revolvably mounted in said frame to contact the opposite side of the wheel, and threaded means to exert lateral frictional pressure of the rolls against the sides of the rim of the machine wheel and regulate the pressure of both of said rolls.
4. A driving device for machines having a running wheel, comprising in combination with a motor having a shaft, a friction wheel fixed on said shaft, a forked member pivotally connected to the motor, a roll revolvably mounted on said member and revolvable threaded means associated with said member to exert lateral pressure of the friction wheel and roll against opposite sides of the running wheel to drive the same.
5. A driving device for machines having a running wheel, comprising in combination with a motor, a friction roll driven by said motor disposed against one side of the running wheel; an idler roll disposed against the opposite side of the wheel, a lever pivoted on said motor to carry said idler roll and means to exert pressure on said lever to press said idler roll and friction roll against the sides of the running wheel and regulate the pressure to drive the same.
6. A driving device for running wheels, having in combination with a motor, a friction roll driven by said motor, a lever, a pivot for the lever on said motor, a pair of idler rolls carried by said lever, and threaded means associated with said lever to exert lateral frictional pressure through the lever and said rolls against an overrunning wheel to drive the same.
7. In a driving device for running wheels and the like, comprising in combination with a motor, a friction roll driven by said motor disposed on the side of a running wheel, a forked lever pivoted on said motor, a pair of idler rolls journalled in the branches of said lever and disposed against the opposite side of the wheel, and threaded means to exert lateral pressure of the friction roll and idler rolls against the running wheel.

In testimony whereof I have signed my name to this application.
